UNITED STATES PATENT OFFICE.

JOSEPH O. MAUBORGNE AND GUY HILL, OF WASHINGTON, DISTRICT OF COLUMBIA.

SYSTEM OF RADIOTRANSMISSION.

Application filed June 16, 1920. Serial No. 389,450.

To all whom it may concern:

Be it known that we, JOSEPH O. MAUBORGNE and GUY HILL, citizens of the United States, and residents of Washington, 5 in the District of Columbia, have invented certain new and useful Improvements in Systems of Radiotransmission, of which the following is a specification.

This invention relates to the art of radio 10 signaling and particularly transmitting radio signals, and a system for use in the practice of the same.

The object of the present invention is an improvement in the method and apparatus 15 for transmitting radio signals whereby a simplification in the equipment required is effected; also more persistent oscillations are obtained in the case of spark discharge methods and further, this system offers a simple 20 method of obtaining directional sending, and a simple means of generating extremely short wave lengths.

In the present application of the art, to 25 accomplish radio transmission an antenna is required and means for tuning the antenna system to resonance with the frequency of the generator used which usually requires complicated and relatively expensive apparatus.

30 In our invention we make use of a wave coil of distributed inductance and capacity on which a wave development is produced by the transmitting source, the wave length of the said wave development depending 35 only upon the electrical constants of the coil and the position of the potential application to said coil, the wave coil by itself constituting the complete antenna system. In its simplest form the wave coil is made in the 40 form of a long helix, uniformly wound with suitable insulating wire, closely spaced so that the inductance per unit length is relatively large. We have found that it is desirable to wind the coil on a material having 45 high insulating properties such as mica or bakelite dielectro. We get, therefore, in a comparatively short coil, the equivalent condition of a long line in the matter of wave development. The electromagnetic waves of the outgoing signals are 50 emitted from each element of the wave coil and we have here a condition where the electrical constants of the coil, the inductance, capacity, and resistance and E. M. F. set up 55 therein by excitation from a suitable source

of energy are all of a distributed character, and the energy is radiated from each element of the coil, making it accordingly an ideal radiating system.

The fundamental principle underlying the 60 use of the wave coil as a transmitter is that there should be applied at some element of the coil, a maximum potential which will set up waves on the coil of a period determined by the electrical characteristics of the coil 65 and the position on the coil of the applied potential.

Our system is equally suitable for damped or undamped waves. We may use a high potential discharge method allowing free 70 oscillations to be set up on the coil, the frequency to be determined by the electrical constants of the coil, and the position on the coil of the applied potential, or we may impress a high frequency potential on the coil 75 and adjust the coil so that its natural wave length should be the same as that of the source of high potential.

We have found that in the use of the discharge method of exciting the coil, the length 80 of the wave or waves set up on the coil depends upon the position of the point of application of the potential to the coil. By shifting the point of application of the energy source to different positions along the 85 coil, moving always in the same direction from the center, two different wave lengths are set up on the coil for each position of the application point except that at the exact center or at either end of the coil, only one 90 wave length is generated. The wave lengths generated on the coil are entirely independent of the construction or constants of the lead, the spark gap and the associated circuits of the source of energy used, but are 95 solely determined by the characteristics of the coil and the position on the coil of the applied potential. When the application point is impressed at the center of the wave coil, each half of the wave coil generates the 100 same wave length and a single wave length is transmitted from the coil. As the point of application is moved away from the center towards either end, the shorter part of the wave coil generates the shorter wave length 105 determined by the constants of that part of the coil between the application point and the end towards which the application point moves. Between the application point and the further end of the coil a longer wave 110

length is generated depending upon the constants of the coil between the application point and the said further end. As the application point is continuously moved towards one end, as referred to above, one of the wave lengths is continuously shortened and the other wave length is continuously lengthened. When the application point is applied at the extreme end of the coil, only one wave length is produced which is the maximum wave length that the coil can generate. When the source of high potential applied to the coil has a frequency of its own, the point of contact on the coil is so adjusted that the actual wave length of the coil will be the same as that of the source of high potential, and in this case, only that part of the coil is active, the natural frequency of which corresponds to the frequency of the impressed source.

As a source of energy we may use any of the well-known means for producing high potentials. It may be a Ruhmkorff coil, a high frequency buzzer, a power buzzer, a high frequency alternator, an arc transmitter of an electron tube transmitter.

We have also discovered that a wave coil antenna possesses remarkable directive qualities. By its use it is possible to transmit signals in any desired direction in space, depending upon the position of the wave coil with reference to horizontal and vertical planes passing through the center of the wave coil.

Since the electro-magnetic waves emitted by the coil are perpendicular to the longitudinal axis of the coil, the waves, therefore, travel in one plane. The wave coil is equally effective in transmitting signals in a vertical plane as in a horizontal plane, and therefore offers suitable means for transmitting signals to or from an airplane station.

While our invention consists primarily in the use of a wave coil and associated apparatus, without what is ordinarily known as antenna and ground connections, our invention also covers the use of such wave coils and associated apparatus, with either antenna or ground connections or both, and this is understood to include the so-called "wired-wireless" connections, provided the principle of setting up waves on the wave coil is used for the purpose of determining the frequency of the transmitted signals.

The principle of operation and the method of using our invention can be better understood by reference to the accompanying diagrammatic figures which show practical embodiments of the invention and form part of this specification.

In all of the figures herewith, the same symbols and nomenclature are used to designate the same apparatus, and therefore reference to the various common symbols will not be repeated, except in cases where it is

necessary to make clear the difference between the various figures.

In the accompanying drawings, Figure 1 is a diagrammatic view of one form of the device used for the transmission of radio signals, in which an induction coil is used as the energy source;

Figure 2 shows a similar diagrammatic view to Figure 1 except that an alternator and high tension transformer have been substituted for the battery and an induction coil of Figure 1 and a condenser shunted around the spark gap;

Figure 3 shows a diagrammatic view similar to Figure 1 but indicates the use of a continuous wave generator instead of an induction coil circuit as shown in Figure 1;

Figure 4 shows a similar diagrammatic view to that shown in Figure 1 except that connection to the wave coil is electro-static instead of direct;

Figure 5 is similar in view showing a unilateral electro-magnetic connection to the wave coil;

Figure 6 is a diagrammatic view showing a tuned circuit in inductive relation to the wave coil;

Figure 7 is a diagrammatic view showing an arrangement for exciting two or more wave coils from the same source;

Figure 8 illustrates another method of exciting two wave coils from a single source of high potential;

Figure 9 shows a diagrammatic view similar to Figure 1 except that one side of the spark gap is grounded;

Figure 10 shows a diagrammatic view similar to Figure 3 except that one side of the continuous wave generator is grounded;

Figure 11 shows an arrangement similar to Figure 1 except that the wave coil is in the form of an arc.

Having more particular reference to the drawings and to Figure 1, A represents the wave coil consisting of a helix of suitably insulated wire, preferably copper, closely wound in a single layer on a suitable insulating tube. We prefer to make the length of the helix greater than its diameter. P indicates a slider making direct contact with the wave coil and capable of being moved along the wave coil.

S represents a spark gap to the terminals of which are connected the terminals of the secondary winding H of the induction coil. The slider P is connected to one terminal of spark gap S by a suitable lead as shown. L represents the low tension winding of the induction coil and I represents the usual iron case. M indicates the vibrator for making and breaking the low tension circuit. B represents a battery and K represents a key in the same circuit for purposes of signaling. The other terminal of the spark gap has no external connection as shown in the figure.

The principle of operation is as follows: On signaling by means of the key K, a high potential is set up across the gap S, one terminal of which is connected to some predetermined point on the wave coil. The potential thus impressed on the coil sets up free oscillations on it, the frequency of which is determined by the electrical constants of the coil and the point of the potential application on the coil.

We have found that the oscillations developed on such a coil, when excited even by a simple induction coil, have extremely small damping, and the radiation from it is in the form of a very pure wave.

Figure 2 shows an arrangement somewhat similar to Figure 1, except that for the spark coil of Figure 1 is substituted a high tension iron core transformer of which H' represents the high tension or secondary winding the terminals of which are connected to spark gap S, of any desired form, which is shunted by a suitable condenser C. L' represents the low tension or primary winding of the transformer, the terminals of which are connected in series with a suitable source of alternating current, D, of any desired frequency, and a key K, for the purpose of signaling.

In the succeeding figures where coil H and spark gap S are shown, it is understood that this coil H can either be the high tension winding of an induction coil as shown in Figure 1, or the high tension winding of a transformer as shown in Figure 2 and described above.

Figure 3 is similar to Figure 1 except that the apparatus for applying potential to coil A by slider P in this case consists of a generator of continuous waves. This generator is indicated in the diagram by V. The circuit connections of this generator are not shown in the figure or in any following figures where a similar arrangement is used as the circuits of the continuous wave generator do not form a part of this invention. We are interested merely in attaching to wave coil A a device so arranged that it will produce a continuous supply of oscillating potential suitable to actuate wave coil A. The generator of continuous waves indicated by V may consist of a high frequency alternator, an arc transmitter, a vacuum tube transmitter, or any other means for generating high frequency oscillations the circuits and the design of apparatus in any of the above systems being arranged so that a high voltage may be applied to coil A.

It will be noted, as shown in the figure, that it is not necessary to have any antenna or ground connection on the coil A or on the generator of continuous oscillations V, as we have found by practice.

In general, if the arrangement of the generator or generator circuits result in the

production of a wave of given frequency, the constants of wave coil A and the position of slider P should be so chosen as to result in the emission of a wave from wave coil A of the same frequency as that applied by the generator through the lead to P.

The generator V may consist of any one of the well-known forms of continuous wave apparatus resulting in the production of either continuous waves, interrupted continuous waves, or modulated continuous waves. In the last case the apparatus is modulated either by a buzzer or a microphone. Hence, the connection shown in Figure 3 may be used either for the production of radio telegraphic or radio telephonic signals of any of the classes described. By the above method we have transmitted wireless telephone conversation in an entirely satisfactory manner.

Figure 4 represents a diagrammatic view of an arrangement similar to Figure 1, the only difference being that in Figure 4, T represents a circular metal plate in electrostatic relation to coil A; this circular plate T taking the place of the sliding contact P in Figure 1.

Figure 5 is similar to Figure 1 except that in place of a sliding contact P there is associated with the coil A a small coil R, one terminal of which is connected to spark gap S. The coil R being so designed that it can slide along the entire length of coil A, the coil R making an electro-magnetic connection to the coil A.

Figure 6 is similar, in general, to Figure 5 except that in this figure the coil R is connected to both sides of the spark gap S through a condenser C₁. The circuit C₁, R, S is tuned, if desired, to a wave length corresponding to the position of coil R on wave coil A.

Figure 7 is similar to Figure 1 except that in this figure, two coils A and A₂ are excited from one side of spark gap S. If sliders P₁ and P₂ are adjusted on their respective coils so as to emit exactly the same wave length, the intensity of the transmitted signals will be greatly increased. This arrangement also enables two different wave lengths to be transmitted at the same time, if desired, by adjusting, say, slider P₂ on coil A₂ so that coil A₂ will emit a different wave length than coil A₁. It is obvious that a multiplicity of coils can be excited in the same manner.

Figure 8 represents another method of accomplishing the result similar to that shown in Figure 7. In Figure 8 the wave coils A₃ and A₄, by means of the respective sliders P₃ and P₄, are connected one to one side of spark gap S and the other to the other side of spark gap S. The method shown of exciting two or more wave coils from the same spark gap or other source is an efficient

method for transmitting with considerable power on very short wave lengths. The main difficulty in transmitting on short wave lengths in the usual systems is that in order to obtain an extremely short wave length, the allowable amounts of inductance and capacity that can be used in tuning the circuits are so small that it is extremely difficult to get an appreciable amount of energy in the antenna or radiating system. This difficulty is obviated by our method as a large number of wave coils, each proportioned to give an extremely short wave length, can be operated in parallel and therefore any desired amount of energy can be obtained merely by the addition of a sufficient number of suitably proportioned coils.

Figure 9 represents an arrangement of apparatus identical with Figure 1 except that the terminal of spark gap S, which is not connected to the coil A, is connected to ground. As stated above, with reference to Figure 1, no ground connection is necessary in our system. We consider however, that in certain applications of this system, and in order to get proper potential relations on the Ruhmkorff coil, that it may be desirable to ground one terminal of the spark gap as shown in the figure. We consider that under certain conditions, and with certain types of wave coil and arrangement of apparatus, an increased efficiency may result from the utilization of a ground connection as shown, although by this method we have found that the directional effects are somewhat neutralized.

Figure 10 is similar to Figure 3 in so far as the apparatus employed is concerned, but in this case, the source of continuous waves V is connected to ground as shown in the diagram.

Figure 11 consists of a diagrammatic view similar to Figure 1. In this case the coil A is made in the form of an arc or is wound upon a flexible rubber tube so that it can be bent in any desired form. This arrangement is of advantage in that the energy is radiated from it in various directions which may be desirable in some cases.

The above specifications and figures are considered to illustrate only some of the elementary forms of this invention and its use. Since this invention primarily consists in the use of a long coil, ungrounded, and not connected to any antenna system, all the various forms of connecting it in circuit are not specified herein as they will, in general, be evident as obvious modifications to any one skilled in the art.

Among some of the obvious modifications are various forms of winding the wave coil, such as using multiple layer coils instead of the single layer herein described.

The slider indicated as T in Figure 4 may have various forms. It may be cylinder

sliding over the coil, or some form of clip for making contact with a single turn of the wave coil.

We claim:

1. A system for transmitting radio signals, comprising a power supply and two or more wave coils, means for simultaneously applying to corresponding points on said coils a suitable high frequency potential from a single source for causing wave developments on said wave coils and means for modulating said power supply for the purposes of signalling. 75

2. A system for transmitting radio signals, comprising a power supply and two or more wave coils, means for causing wave developments on said coils upon the simultaneous application to different points on said coils, a suitable high frequency potential from a single source for simultaneous radiating waves of two or more different lengths, and means for modulating said power supply for purposes of signalling. 80 85

3. A system for transmitting radio signals employing a wave coil of distributed inductance and capacity in the form of an open circuit and having a non-metallic core, on which wave coil a wave development is produced by the connection of a source of high frequency to only one element of said wave coil, the wave length of said wave development depending solely upon the electrical constants of said wave coil and the elements of said wave coil to which said high frequency source is applied. 95 100

4. A system for transmitting radio signals employing a wave coil of distributed inductance and capacity, said wave coil being in the form of an open circuit and having a non-metallic core, in which wave coil a wave development is produced by the application of a potential to only one element of said wave coil, the wave length of said wave development depending solely upon the electrical constants of said wave coil and the element of said wave coil to which said potential is applied. 105 110

5. A system of transmitting radio signals employing a wave coil of distributed inductance and capacity, said wave coil being in the form of an open circuit and having a non-metallic core, on which wave coil a wave development is produced by the application of a potential to an element of said wave coil, the wave length of said wave development depending solely upon the electrical constants of said wave coil and the element of said wave coil to which said high potential is applied, and means for modulating high potential source for signalling 115 120 125 purposes.

6. A system for transmitting radio signals employing a wave coil of distributed inductance and capacity, said wave coil being in the form of an open circuit and having a 130

- non-metallic core, on which wave coil a wave development is produced by the application of a high potential to an element of said wave coil, the wave length of said wave development depending solely upon the electrical constants of said respective wave coils and the elements of said coils to which said high frequency source is applied. 55
- 5 7. A system for transmitting radio signals employing wave coil of distributed inductance and capacity, said wave coil being in the form of an open circuit and on which a wave development is produced by causing a high potential from a modulated spark discharge in a non-tuned local circuit to be applied to only one element of said wave coil, the wave length of said wave development depending solely upon the electrical constants of said wave coil and the element of said wave coil to which said high potential is applied. 65
- 10 8. A system for transmitting radio signals of a single frequency employing two or more wave coils each having distributed inductance and capacity in the form of an open circuit, each of said wave coils having a wave development of the same frequency produced by simultaneously causing a modulated single high frequency source to be connected to corresponding elements of said wave coils, the wave length of said wave developments depending solely upon the electrical constants of said respective wave coils, and the elements of said coils to which said high frequency source is applied. 70
- 15 9. A system for simultaneously transmitting the same radio signals on two or more frequencies employing two or more wave coils each having distributed inductance and capacity in the form of an open circuit, each wave coil having produced thereon a wave development of different frequency by causing a single modulated high frequency source to be connected to different elements of said wave coils, the difference in the resulting wave lengths of said wave developments de-
- pending solely upon the electrical constants of said respective wave coils and the elements of said coils to which said high frequency source is applied. 75
- 20 10. A system for transmitting radio signals comprising a wave coil of distributed inductance and capacity, in the form of an open circuit, a high potential source electrically connected to only one element of said wave coil effecting thereby a wave development on said wave coil, means for modulating said source of high potential for purposes of signalling. 80
- 25 11. A system for transmitting radio signals comprising a wave coil having distributed inductance and capacity, said wave coil being in the form of an open circuit and having a non-metallic core, said wave coil being adapted to have a wave development produced thereon by the application of a high frequency potential to only one element of said coil, means for varying the point of application of said potential for the purpose of obtaining a maximum energy radiation from said wave coil, means for producing said high frequency potential and means for modulating same. 85
- 30 12. A system for transmitting radio signals comprising a multiple layer wave coil having distributed inductance and capacity, said wave coil being in the form of an open circuit and having a non-metallic core, said wave coil being adapted to have a wave development produced thereon by the application of a high frequency potential to only one element of said coil, means for varying the point of application of said potential for the purpose of obtaining a maximum energy radiation from said wave coil, means for producing said high frequency potential and means for modulating same. 90
- 35 13. A system for transmitting radio signals comprising means for causing wave developments on two or more antennæ by simultaneously imposing thereon a suitable potential from a single source, the frequencies of the two or more wave developments being respectively adjustable by adjustments of the antennæ. 95
